(57) **CLAIM**

The ornamental design for a waste receptacle, as shown and described.

DESCRIPTION

FIG. 1 is a front perspective view of a first embodiment of a waste receptacle;

FIG. 2 is a right side elevation of the waste receptacle of FIG. 1, the left side elevation (not shown) being a mirror image thereof;

FIG. 3 is a top plan view of the waste receptacle of FIG. 1; FIG. 4 is a bottom plan view of the waste receptacle of FIG. 1;

FIG. 5 is a front perspective view of a second embodiment of a waste receptacle;

FIG. 6 is a right side elevation view of the waste receptacle of FIG. 5, the left side elevation (not shown) being a mirror image thereof;

FIG. 7 is a top plan view of the waste receptacle of FIG. 5; and,

FIG. 8 is a bottom plan view of the waste receptacle of FIG. 5.

The netting is partially shown in FIGS. 3,4,7 and 8 for convenience of illustration.
